HANDLE FOR A GROOMING AID FOR PETS

Robert W. Sleith, Wilbraham, Mass., assignor to
Suburban Plastics, Inc., Three Rivers, Mass.

Filed Sept. 20, 1971, Ser. No. 182,293

Term of patent 14 years

Int. Cl. D30—99

U.S. CL. D30—40

FIG. 4.

FIG. 5.

FIG. 1 is a side elevational view of a handle for a grooming aid for pets showing my new design;

FIG. 2 is a top plan view thereof;

FIG. 3 is an end elevational view toward one end of the handle for a grooming aid for pets;

FIG. 4 is a bottom plan view; and

FIG. 5 is an end elevational view of the handle for a grooming aid for pets toward the handle end thereof.

I claim:

The ornamental design for a handle for a grooming aid for pets, as shown and described.
